UNITED STATES PATENT OFFICE

126,135

DESIGN FOR A COMBINED ASH TRAY AND ADVERTISING HOLDER

John William Nichols, Dallas, and Harold Robert
Bisby, Garland, Tex.

Application June 18, 1940, Serial No. 93,160

Term of patent 7 years

To all whom it may concern:

Be it known, that we, John William Nichols and Harold Robert Bisby, residing respectively, at Dallas and Garland, in the county of Dallas and State of Texas, have invented a new, original, and ornamental Design for a Combined Ash Tray and Advertising Holder, of which the following is a specification, reference being had to the accompanying drawing, forming a part thereof, and in which:

Figure 1 is a perspective view of the combined ash tray and advertising holder showing our new design.

Figure 2 is a vertical sectional view thereof.

Figure 3 is a transverse sectional view.

We claim:

The ornamental design for a combined ash tray and advertising holder, as shown.

JOHN WILLIAM NICHOLS.
HAROLD ROBERT BISBY.
